UNITED STATES PATENT OFFICE.

HATTIE W. HILLER, OF NEW YORK, N. Y.

SHOE-LACING.

SPECIFICATION forming part of Letters Patent No. 699,869, dated May 13, 1902.

Application filed July 27, 1901. Serial No. 69,895. (No model.)

To all whom it may concern:

Be it known that I, HATTIE W. HILLER, a citizen of the United States, and a resident of the borough of Manhattan, in the city and

5 State of New York, have invented a new and useful Shoe-Lacing, of which the following is a specification.

My invention relates to shoe-lacings, with the object in view of providing a shoe-lacing 10 capable of being tied in a multibow or rosette knot at the front of the shoe or wherever the lacing may be employed.

My invention consists, broadly, in a shoe-lacing composed of a plurality of separable 15 longitudinal sections extending along that portion of the lacing which is intended to be used to form the knot.

A practical embodiment of my invention is represented in the accompanying drawings, 20 in which—

Figure 1 represents the lacing as it appears when in use on the front of a shoe. Fig. 2 is a plan view, and Fig. 3 is an edge view.

The separable sections extend along the 25 end portions or along that portion or those portions of the lacing which is or are intended to be used to form the knot and are preferably united at their outer ends either temporarily or permanently by means of tips for 30 conveniently passing them through the eyelets.

The shoe-lacing, as represented in the several figures, comprises a central body portion *a*, formed of a single or non-separable part, 35 and end portions composed of a plurality of longitudinal parts or sections, in the present instance three parts each, those of one end portion being denoted by *b b' b''* and those of the opposite end portion being denoted by 40 *c c' c''*. These several parts at the end portions of the shoe-lacing are shown united at their outer ends by means of tips *d* and *e*.

These may be stripped from the ends after the lacing has been once inserted in the shoe, or they may remain in their position on the ends, 45 as preferred.

When the lacing has been inserted, the double-bow knot will be composed of six loops, which may be arranged by a little skill in tying to stand radiating from a common center, as shown in Fig. 1, presenting a rosette 50 appearance.

It is obvious that the number of parts may be increased or diminished at pleasure and that the width and thickness of the several 55 parts may be made a matter of selection. Hence I do not wish to limit myself strictly to the structure herein shown and described; but

What I claim is—

1. A shoe-lacing separated throughout a portion of its length into a plurality of longitudinal parts or sections, substantially as set forth.

2. A shoe-lacing comprising a central non- 65 separable body portion included between portions separated into a plurality of longitudinal sections or parts, substantially as set forth.

3. A shoe-lacing comprising a central non- 70 separable body portion, portions on the opposite sides of the non-separable body portion separated into a plurality of longitudinal parts or sections and tips for uniting the several sections or parts, substantially as set 75 forth.

In testimony that I claim the foregoing as my invention I have signed my name, in presence of two witnesses, this 26th day of July, 1901.

HATTIE W. HILLER.
